COMBINED DISPLAY STAND AND DISPENSER FOR TOOTHBRUSHES AND THE LIKE

Harry G. Schuett, Maywood, Ill.

Application January 9, 1959, Serial No. 54,118

Term of patent 14 years

(Cl. D80—5)

Fig. 1

Fig. 2

Fig. 3

Fig. 4

Fig. 1 is a perspective view of a combined display stand and dispenser for toothbrushes and the like embodying my new design, the toothbrush packages shown in broken lines being for illustrative purposes only;

Fig. 2 is a front elevational view thereof;

Fig. 3 is a top plan view thereof; and

Fig. 4 is a left side elevational view thereof, the right side being a mirror image thereof.

The rear and bottom are open as indicated in Figs. 1, 2 and 3.

I claim:

The ornamental design for a combined display stand and dispenser for toothbrushes and the like, as shown and described.
